UNITED STATES PATENT OFFICE

ARTHUR P. PAINE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

TUBE FRAME FOR AXMINSTER LOOMS

Application filed May 18, 1928. Serial No. 278,891.

This invention relates to Axminster looms and it is the general object of the invention to provide an improved tube frame and transporting chain to the end that the tube frame may be held more securely against accidental displacement with respect to the transporting chain.

In my prior Patent No. 1,493,561 there is shown a transporting chain having projecting tongues which are adapted to be interlocked with a tube frame having a sliding locking bar. Actual operation of the construction shown in the aforesaid patent shows the desirability of being able to direct the tongues on the transporting chain more accurately into operative position with respect to the holding plunger, and it is accordingly an important object of my present invention to provide the brackets of the tube frame and also the clutch which releases the tube frame from the tongues with guiding surfaces which operate to guide the tongue more accurately toward the holding plunger when the tube frame is being attached to the transporting chain.

It is also found that the releasing tongue which is carried by the clutch may not operate to move the holding or interlocking plunger in properly retracted position to effect complete release of the attaching fingers on the transporting chain and it is a further object of my invention to provide a construction which will insure releasing of the finger by the plunger.

It is a more specific object of my present invention to provide the releasing tongue as a part of one of the studs customarily provided as a part of the releasing clutch.

Experience has shown that the plunger shown in my aforesaid patent is likely to be pushed inwardly too far so to become disengaged from the guide therefor, with the result that the plunger does not return to interlocking position. It is a further object of my present invention to provide means whereby the movement of the plunger will be properly limited so that the same will always be located in the guide therefor and thus be required to move into locking rela-

tion with the fingers when the unlocking tongue is withdrawn.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a side elevation of a tube frame made according to my present invention and the adjacent part of the transporting chain together with the sprocket around which the chain moves,

Fig. 2 is an enlarged vertical section on line 2—2 of Fig. 1, showing the tube frame locked in position with respect to the chain,

Fig. 3 is a view similar to Fig. 2 but showing the tube frame unlocked and in readiness for movement from the transporting chain, the clutch which effects the release being shown in section,

Fig. 4 is an end view taken in the direction of arrow 4, Fig. 2,

Fig. 5 is a detailed horizontal section on line 5—5 of Fig. 3, and

Fig. 6 is a detailed view of the lower end of the attaching finger showing the head of the plunger.

Referring particularly to Fig. 1, I have shown the so-called pull over shaft 10 of an Axminster loom and have indicated the lower portion of a sprocket 11 which is supported by and moves with the shaft. The transporting chain 12 is formed of single links 13 and double links 14. Secured to one of the double links 14 of each pair of double links is a tube frame supporting finger 15 the lower end of which as shown in Fig. 6 is provided with a slot 16 opening into a somewhat wider slot 17. The outer end of each finger may be tapered as at 18 to facilitate the operations to be described hereinafter.

Tube frame 19 is preferably made of a metallic tube having secured thereto a bracket or head 20 as by means of screws 21. The bracket has an upwardly extending spool bearing portion 22 on which is 100

mounted spool S. Formed as part of the head 20 is a U-shaped member 23 inserted within the metallic bar 19 and secured thereto by means of screw 24. The outer 5 intermediate portion of said member 23 is formed with a vertical wall 25 which is spaced from the vertical portion of the spool bearing portion 22 as shown in Fig. 2 and the lower end of said wall 25 is provided with a slot 26 to afford access to the slot 16 in the finger 15 when the parts are in the position shown in Fig. 4.

A spring pressed holding or locking plunger 27 has a head 28 adapted to extend 15 through the enlarged slot 17 and engage the shoulders 29 defined by the narrower slot 16 when the parts are in their normal assembled position such as indicated in Figs. 1 and 2. A compression spring 30 is interposed between the head 28 and an upright wall 31 formed as part of the head 20 and the effect of said compression spring 30 is to move the head 28 toward the wall 25, or outwardly.

Under normal conditions the head 28 will 25 be held by the spring 30 within the slot 17 and will rest on the shoulders 29 as shown in Fig. 2. When it is desired to disconnect the tube frame from the transporting chain 30 the head 28 will be moved to the left as viewed in Fig. 2 until said head is entirely clear of the shoulders 29, after which the tube frame may be lowered.

The clutch C as shown more particularly 35 in Figs. 1, 3 and 5 includes a body 32 having a lip 33 projecting from the under side thereof to lie under the bar 19. Secured to the clutch is an upper stud 34 by means of which the clutch may be oscillated around 40 a lower stud 35 which is secured to the transporting arm 36 a portion of which is shown in Fig. 1. It is to be understood that said arm 36 has an inward movement to disconnect the tube frame from the chain 45 and then a downward movement to move the tube frame toward tuft forming position, and that there will be one clutch on each side of the loom so that both ends of the tube frame may be supported.

The matter thus far described is substantially the same as set forth in my aforesaid patent and with the exception of certain details to be noted hereinafter forms no part of my present invention.

In carrying my invention into effect I 55 provide the clutch C with a downwardly and inwardly inclined wall 40 and provide the spool bearing 22 with a corresponding downwardly and outwardly inclined wall 60 41. These inclined walls cooperate to guide the fingers into the space between the spool bearing 22 and the wall 25. The clutch face 40 terminates in an overhang 42 under which 65 is located the wall 25, so that as the tube frame is raised by the clutch the finger 15

will be guided into the proper space provided therefor, the overhang protecting the wall 25 and preventing engagement of the latter by the finger.

As shown particularly in Fig. 5 the stud 70 35 is provided with a slabbed extension or tongue 50 which is sufficiently narrow to extend into the narrow slot 16. The stud may be held in any one of a plurality of positions by a set screw 51 and has a shoulder 52 which limits movement of the stud to the left as viewed in Fig. 3. The lower portion of the spool bearing 22 is recessed as at 53 to receive the tongue 50 and it will be apparent from an inspection of Fig. 3 75 that because of the recess 53 said tongue may extend slightly beyond the inner face of the finger 15, so that there will be no possibility of the head 28 which is engaged by the tongue 50 extending over any portion of the finger 15. As the tube frame and clutch start downwardly, therefore, the head will be to the left of the inner face of the finger and will be held in this position 80 throughout the movement of the tube frame 85 toward and from tuft forming position.

In order that the head 28 may always 90 remain in the guide opening 60 provided therefor in the spool bearing 22 and communicating with the recess 53, I provide the left hand end of the plunger 27 with a shoulder 61 and a reduced end 62 which projects through the wall 31. The shoulder 95 by its engagement with the wall 31 prevents the head 28 from moving out of the slot or opening 60, and there is therefore no chance for the head to get in such a position that it may not return to proper position to have interlocking engagement with the fingers.

From the foregoing description I believe 100 the operation of the device will be apparent. The clutch is given the previously described downward movement with the parts in the position shown in Fig. 3, and then upon the return upward movement the clutch is 105 moved away from the tube frame, that is, the clutch shown in Fig. 3 will be moved to the right so that the head 28 may move to the position shown in Fig. 2 to have holding engagement with the corresponding finger 15.

From the foregoing it will be seen that I 110 have provided a clutch and spool bearing so formed as to guide the finger 15 into the space properly provided therefor and that the overhang 42 operates to protect the wall 25 and keep the same from having such engagement with the finger 15 as would prevent proper cooperation of the parts. Also, the recess 53 permits the advancing end of 115 the tongue to move the head 28 beyond the inner vertical face of the finger 15 thereby insuring proper releasing of the tube frame with respect to the transporting chain. It 120 will further be seen that the stud 35 is 125 130

especially formed, having a tongue to engage the head 28 and move downwardly through the slot 16. It will also be noted that by reason of the shoulder 61 I have prevented disengagement of the head 52 with respect to the opening 60 in the bearing 22.

Having thus described my invention it will be seen that changes and modifications 10 may be made therein by those skilled in the art without departing from the spirit and scope of the invention and I do not wish to be limited to the details herein disclosed, but what I claim is:

15 1. In an Axminster loom having a transporting chain and a tube frame, a finger on the chain, a plunger on the tube frame to engage the finger to support the tube frame from the chain, said finger having a vertical slot in the lower portion thereof, a clutch to support the tube frame, a stud carried by the clutch and having a thin vertical tongue to pass through the slot in the finger to engage the plunger and move the 20 latter out of engagement with the finger, said stud having a smooth cylindrical surface to extend through the clutch to be capable of sliding therethrough to adjusted angular and longitudinal position, said 25 tongue thereby being capable of assuming a position to register with the slot, and means to hold the stud to the clutch.

2. In an Axminster loom having a transporting chain and a tube frame, a finger on the chain, a plunger on the tube frame to engage the finger to support the tube frame from the chain, said finger having a vertical slot in the lower portion thereof, a clutch to support the tube frame, a stud carried by 30 the clutch and having a thin vertical tongue to pass through the slot in the finger to engage the plunger and move the latter out of engagement with the finger, said stud having a smooth cylindrical surface to extend 35 through the clutch to be capable of sliding therethrough to adjusted angular and longitudinal position, said tongue thereby being capable of assuming a position to register with the slot, means to hold the 40 stud to the clutch, and a shoulder on the stud to receive a force capable of moving the clutch toward the tube frame.

45 In testimony whereof I have hereunto affixed my signature.

50 ARTHUR P. PAINÉ.
